US0D1073076S

(12) **United States Design Patent** (10) **Patent No.:** **US D1,073,076 S**
(45) **Date of Patent:** **** Apr. 29, 2025**

(54) **WEARABLE PERSONAL MONITORING DEVICE**

(71) Applicant: **Seer Medical Pty Ltd.**, Melbourne (AU)

(72) Inventors: **Kyle Damon Slater**, Melbourne (AU); **John Lloyd Grant**, Melbourne (AU)

(73) Assignee: **SEER MEDICAL PTY LTD.**, Melbourne (AU)

(**) Term: **15 Years**

(21) Appl. No.: **29/765,365**

(22) Filed: **Jan. 7, 2021**

(30) **Foreign Application Priority Data**

Jul. 10, 2020 (AU) 202013790

(51) **LOC (15) Cl.** **24-02**

(52) **U.S. Cl.**

USPC **D24/186**

(58) **Field of Classification Search**

USPC D24/186, 187, 165–168, 200, 231

CPC A61B 2562/164; A61B 2562/16; A61B

5/14532

(57) **CLAIM**

The ornamental design for a wearable personal monitoring device as shown and described.

DESCRIPTION

FIG. 1 is a top front perspective of the wearable personal monitoring device;

FIG. 2 is a bottom front perspective thereof;

FIG. 3 is a top rear perspective thereof;

FIG. 4 is a front elevation thereof;

FIG. 5 is a rear elevation thereof;

FIG. 6 is a right side elevation thereof;

FIG. 7 is a left side elevation thereof;

FIG. 8 is a top plan view thereof; and,

FIG. 9 is a bottom plan view thereof.

The broken lines illustrate portions of the wearable personal monitoring device that do not form part of the claimed design.

1 Claim, 9 Drawing Sheets
